UNITED STATES PATENT OFFICE

FRANK C. STOWELL, OF MEDFORD, MASSACHUSETTS

RAIL AND TIE PLATE

Application filed May 21, 1928, Serial No. 279,237. Renewed October 10, 1930.

My invention relates to the prevention of longitudinal creeping of the rails over the ties of a railroad track and holding track to gauge. To the former feature I shall principally direct my discussion but do not wish to be considered as limiting myself thereby, as my rail and my tie plate are both adaptable to all other functions of rails and tie plates in railroad track.

Up to the present the metal rails for a railroad track have been rolled with the lower side of the base a flat smooth surface, all parts of which lie within a single plane. Such surface resting upon the railroad ties or tie plates, offers only a slight frictional resistance to the well known tendency of the rails to creep longitudinally, generally in one direction, but some times in periodic alternation from various causes.

At present, to check this creeping, various forms of so-called rail anchors or anti-creepers are fastened to the rails, usually four or six to each rail length, and which by protrusion below the rail base, contact with the ties in the ballast. These rail anchors engage the rail through spring or wedge grips, or askew gripping of the rail base from unbalanced pressure against the ties. The pressure on the tie is always of one anchor only at one or other end of the tie. These anchors retard rail movement only in one direction and hang useless in the event of any backing or reverse movement of the rail as is not uncommon. They bruise the wood and tend to skew the ties from the unbalanced pressure at one end. Naturally some break or become loose and fall off. Their efficiency is limited.

To prevent rail creeping I have devised a new form of railroad track rail, and tie plate, providing for interengagement which prevents the rails from moving longitudinally in either direction, and maintains more uniformly gauge and the original spacing between the rail ends at the joints. My new rail as contemplated by my invention also results in a more uniform distribution of the metal in base, web and head and thus makes possible a more uniform cooling which is beneficial in manufacturing.

The objects may be attained by the mecha-

nisms illustrated in the accompanying drawings in which:

Fig. 1 is a transverse section of the rail and plate.

Fig. 2 a fragmentary longitudinal section 55 of the same.

Fig. 3 is a plan view of a typical tie plate.

Fig. 4 is a transverse section of a modified form of plate.

Fig. 5 a fragmentary section of a rail base 60 in accordance with Fig. 1.

Fig. 6 a bottom face view of such a rail.

Fig. 7 is a similar view of a modified form.

Fig. 8 a transverse section similar to Fig. 1, but of a modified form. 65

Fig. 9 an edge view of a key such as shown in Fig. 8.

Fig. 10 is a longitudinal vertical section through the rails, key, and tie plate.

While the interlocking of the rails with the tie plates and interlocking key may, in virtue of the weight of the rails and their load, be effected by any suitable arrangement of reentrant or protruding faces or parts as between the base of the rail and the top of the tie plates, I illustrate only a few forms which I think best adapted to use.

I have indicated in Fig. 1 a corrugated longitudinal groove *a* rolled in the base of rail *A*, which may be continuous the whole rail length or intermittent, but if intermittent should be so spaced as to engage with the tie plates. I have indicated at *C* a common form of shoulder tie plate but in which a narrow recess *c* is rolled. For such I provide a double locking auxiliary key *B* rolled with protruding top notches or projections *b* to mesh with corresponding reentrant faces in the groove *a* of the rail *A*.

Referring to Fig. 2 which is a longitudinal cross section of the rail, locking key and tie plate *C*, it will be observed that as therein shown the tie plate recess *b* extends only in part across the tie plate and in consequence locking key *B* is held in place against longitudinal rail thrusts. Such structure may obviously be varied. The plate recess *b* as shown is slightly longer than the locking key *B* to allow it a limited longitudinal movement to facilitate the full meshing of the 100

notches in relaying a new rail upon previously spiked plates on the ties.

The locking key B shown in Figs. 1 and 2 and resting in the plate recess b is an arrangement by which the tie plate C without the key B could if desired be used in connection with the present flat base rail. It would present a plain top surface with the exception of the recess b, which however is not in itself an uncommon form of tie plate as the recess is often formed to lighten the plate.

Recess b could be rolled of course continuously across plate B and locking key B made with deflected ends, which contacting with the edge of tie plate would restrain key B longitudinally.

In Fig. 4 I have shown a cross section of tie plate C through the center line at the center or greatest elevation of the notches. The integral corrugated elevation c¹ may be continuous across the full width of the plate, or of shorter length.

In an installation of new rail and new tie plates at the same time, of any of the details outlined, complete meshing and full seating of the rail on the tie plates would be effected by slight longitudinal hand adjustment one way or the other of the plates on the ties, as necessary. In the event of relaying a new rail of the same type on the old tie plates, remaining spiked in the original fixed position upon the ties, the rails being bolted together with a predetermined and fixed spacing at the rail ends, the corrugations in the rail base would not necessarily fully mesh with the corrugations in each individual plate. The apexes might even contact but the sharp edges in contact are so restricted in area that either the weight of the rail itself or the first rolling load upon it, would deflect the rail into full seat and mesh with the tie plates. This would be effected rather the easier in case of the plates using the locking key B which provides for ready movement longitudinally to accommodate the conditions. Where the corrugations are a fixed part of the plate itself, the full seating and meshing would be effected by slight movement of the plate itself from such slackness as is usual in the spikes in the spike holes or even from the ties in the ballast.

Fig. 4 is a sectional elevation of a tie plate C¹ showing the notched raised rib c¹ as fixed and rolled integrally with the plate in contrast with tie plate C as shown in Figs. 1 and 2, wherein the permanent raised notched rib c¹ is replaced by a movable notched key B. The contour and top notching in either case may be the same as both are designed to mesh with the reentrant notches a in base of rail A.

These reentrant notches a may be pyramidal or otherwise to correspond and fit their recesses in the rail base.

This diamond shape is only suggested as a form of construction and may be replaced by

any form of tooth and reentrant recess to fit the same. Such forms of elevated tooth or notch on the plate and receiving indentures in the rail base may be used as are most satisfactory to the process of rolling rails and plates and to the locking of same in service as hereinabove described.

While I have discussed my invention with particular reference to preventing the longitudinal creeping of the rails in a railroad track as that is a feature of immediate and pressing need, it will be understood that the principles here involved may be applied to railroad track rails and tie plates in other fields where conditions make possible the utilization of the principles involved. Similarly, such modifications and variants of structure and design as clearly fall within the limits of the appended claims are to be regarded as within the intent of my invention.

As heretofore suggested my invention contemplates principles which are entirely consistent with established track engineering as well as with steel rolling practice. Rails rolled in accordance with my invention are structurally more perfect because the base groove permits a proportioning of thickness in the metal as between base and web of rail so that uniformity in cross section cooling is made possible. I assert this feature as novel and in itself an important contribution to the art.

What I therefore claim and desire to secure by Letters Patent is:

1. A railway track rail having a flat face base provided with a recess having plate engaging transverse members triangular in cross section, a plate having a longitudinal channel, and a locking key confined in said channel and having transverse members interengageable with those of the rail and of like cross section.

2. A railway track rail having a flat face base reentrantly recessed to form plate engaging transverse members triangular in cross section, a plate having a longitudinal channel, and a locking key adjustably confined in said channel and having transverse members interengageable with those of the rail and of like cross section.

3. A railway track rail having a flat face base provided with a reentrant groove having plate engaging transverse members triangular in cross section, a plate and a locking key member thereon and having transverse members interengageable with those of the rail and of like cross section.

4. A railway track rail having a flat face base provided with a reentrant groove having plate engaging transverse members triangular in cross section and adapted to interlock with a plate carrying transverse members interengageable with those of the rail and of like cross section.

5. A railway track rail having a flat face base reentrantly recessed throughout its length in a series of pyramidal pockets adapted to be interlocked to a base plate carrying similarly shaped projections.

5 In testimony whereof I affix my signature.

FRANK C. STOWELL.
